UNITED STATES PATENT OFFICE.

THOMAS J. HALLAM, OF LYNN, MASSACHUSETTS, ASSIGNOR, BY MESNE ASSIGNMENTS,
TO UNITED SHOE MACHINERY CORPORATION, OF PATERSON, NEW JERSEY, A COR-
PORATION OF NEW JERSEY.

EYELETING-MACHINE.

1,271,722.

Specification of Letters Patent.

Patented July 9, 1918.

Application filed November 22, 1915. Serial No. 62,788.

To all whom it may concern:

Be it known that I, THOMAS J. HALLAM, a citizen of the United States, residing at Lynn, in the county of Essex and State of Massachusetts, have invented certain Improvements in Eyeletting Machines, of which the following description, in connection with the accompanying drawings, is a specification, like reference characters on the drawings indicating like parts in the several figures.

The present invention relates to machines for setting eyelets or similar fastening devices and more particularly to machines for setting blind or invisible eyelets in boots and shoes.

In setting such eyelets it has been customary to employ an upsetting tool having a shouldered upsetting surface of a diameter sufficiently small to be passed through the hole which constitutes the lacing passage in the uppermost layer of the material. In shoes of many styles, and particularly those having invisible eyelets, it is desirable to make the lacing passage as small as possible. Consequently the attempt has been made to reduce the diameter of the upsetting die to a minimum. In dealing with certain kinds of eyelets, however, a smoother and more satisfactory clenching of the eyelet barrel is secured by the employment of an upsetting die having a diameter greater than the diameter of the lacing passage hole. In one of its important aspects the present invention consists in an upsetting tool having a shouldered upsetting surface formed in a plurality of expandable die sections. Such an upsetting die may be inserted through a relatively small lacing passage hole and then expanded to such a diameter as will insure a smooth and reliable clenching operation upon all eyelets which may be presented for insertion. As herein shown the upsetting tool is provided with a recess above its setting shoulder in order that the expanding operation may take place without stretching the hole. This feature is not essential in all cases but has been found desirable in handling certain classes of work.

Expandable upsetting dies have been used heretofore to some extent in machines for setting blind or invisible eyelets. In these

machines the expandable die has been utilized to remove the eyelets from the raceway, in this respect assuming the function usually carried out by the spindle of the lower setting die. As distinguished from this arrangement, and in accordance with another feature of the present invention, it is proposed to employ a tool distinct from the expandable upsetting die for removing the eyelets from the raceway. Such an arrangement possesses the advantage that the upsetting die, which is necessarily of somewhat delicate construction, is relieved of one operation which in the machines heretofore used has occasionally caused breakage.

Another feature of the invention consists in an expandable upsetting die so constructed and arranged that its position and movement is at all times positively controlled. Such construction has been found to contribute largely to the accurate and reliable operation of the machine. As herein shown the desired results are effected by mounting the expandable upsetting die rigidly but adjustably in the top set holder of an eyeletting machine of well-known construction.

Still another feature of the invention consists in an expandable upsetting die so constructed and arranged as to effect the automatic feeding of the work in addition to its function of setting the eyelets.

Other features of the invention consist in the combination with an expandable upsetting die, of a die expanding member constructed and arranged to enter the expandable portion of the die for a substantial distance and so rigidly support the individual sections thereof. This expedient has been found useful in reducing the liability of breakage of the die.

Other features of the invention relate to various details of construction in the mounting of the expandable die and the expanding tool. These and other features of the invention will be best understood and appreciated from the following description of a preferred embodiment thereof selected for purposes of illustration and shown in the accompanying drawings, in which,—

Figure 1 is a view in perspective of so much of an eyeletting machine as is necessary to understand the invention;

Fig. 2 is a view of part of the machine in front elevation showing the eyelet setting tools in section;

Fig. 3 is a sectional view showing the eyelet setting tools in the position which they occupy at the conclusion of the clenching operation, and

Fig. 4 is a view in perspective of the upsetting die and a portion of the expanding tool.

The invention is herein shown as embodied in the well-known Perfection eyeletting machine but it will be apparent that any other eyeletting machine will do as well.

The machine frame 10 is provided with bearings 12 in which reciprocates a vertically movable plunger 14 having the setting or eyelet inserting dies 16 adjustably mounted in its upper end. A stationary work plate 40 is secured to the machine frame and is cut away to permit the passage of the setting and punching tools. The frame also carries a swinging lever 48 in which the upsetting die, to be presently described, is mounted. At one side of the lever 48 is a second lever 44 which carries a punch 42 arranged to coöperate with a punching die 46 disposed beneath it in a slot in the work table 40. A presser foot 47 of the usual construction is provided for holding the work stationary between the feeding steps. A raceway 70 is arranged to supply the eyelets successively to the die 16. The actuating mechanism for the various tools is not illustrated herein as it forms no part of the present invention and may well be of similar construction to the corresponding mechanism of the Perfection eyeletting machine.

The upsetting die comprises a tubular shank 58 merging at its lower end into a plurality of resilient sections 60. Near its lower end the upsetting die has an outwardly projecting shoulder upon the lower surface of which is formed the upsetting surface 64. The upsetting surface is recessed or corrugated to form a number of sharp ribs 62 which act to split the barrel of the eyelet at points half way between the edge of each section. This insures that the metal of the eyelet barrel shall extend continuously across the opening which occurs between adjacent sections of the die when in expanded condition. Above the shoulder the upsetting die is contracted in diameter so that it may be expanded after its insertion through the work without stretching the hole.

The upsetting die is received within a tubular holder 49 which in turn is received within a bore in the forward end of the lever 48. The holder 49 is slotted for a portion of its length so that it may be contracted upon the upsetting die and also held in place in the lever 48 by a set screw 51. The

holder 49 is threaded at its upper end 50 65 into the upper end of the bore in the lever 48 and may be adjusted by being turned in the proper direction. The holder 49 at its upper end 50 is also internally threaded to receive an adjustable abutment piece 70, 56, provided with a threaded screw 52, by which the position of the upsetting die in the holder is adjustably determined. It will be seen that the construction above described affords convenient provision for adjusting the holder 49 in the lever 48 and the upsetting die in the holder and that when such adjustments have been effected all parts are rigidly held in their adjusted positions.

The eyelet inserting die 16 is provided with a spindle 18 which serves to remove the eyelet from the raceway, guide it to the upsetting die and also expand the upsetting die. The upper end of the spindle is tapered and shaped to enter and expand the upsetting die. Below its tapered end the spindle has a cylindrical portion 20 which passes into the expandable upsetting die for a substantial distance, as shown in Fig. 3. Below the cylindrical portion 20 the spindle has a shoulder of substantially the same diameter as the diameter of the expanded upsetting die, so that the diameter of the cylindrical spindle 18 is suitable for guiding an eyelet against the upsetting surfaces. At its lower end the spindle is threaded into a slideable angle piece 24 which extends outwardly through a slot in one side of the plunger 14 and is guided for vertical movement in a path parallel to that of the plunger. Beneath the inwardly projecting end of the angle piece 24 is disposed a plunger 26 held normally in an elevated position by a spring 30. The plunger 26 and spring 30 are inclosed in a tubular holder 28 which in turn is movable in the bore of the plunger 14. The lower end of the holder 28 is shouldered and reduced in diameter so that it may enter a compression spring 32 of greater strength than the spring 30 above mentioned.

A plate 34 is secured to the machine frame adjacent to the plunger 14 and is shaped to form a part of the bearings for the end of the angle piece 24. At its upper end the plate 34 carries an adjustable stop 36 which is arranged to engage the angle piece 24 during the upward movement of the latter and arrest it at a predetermined point. This stop 36 is held in position by a screw 37 120 passing through an oblique slot in the plate 34. By loosening the screw 37 and moving the stop 36 sidewise, its vertical position may be varied and the upward limit of movement of the angle piece 24 and the spindle 18 thereby accurately determined.

In setting invisible eyelets in a shoe upper, for example, the upper is presented

upon the work table 40 with the point at which the first eyelet is to be set beneath the punch 42 and the outer or leather portion 80 uppermost. The machine is then set 5 in operation whereupon the punch descends and perforates both parts of the upper. The punch is then elevated and moved toward the right (Fig. 1) to an inoperative position. The expandible upsetting die is 10 next moved into position above the holes thus formed and is lowered sufficiently to bring the shoulder of its upsetting surface through the leather portion 80 and substantially flush with the inner surface of the lining portion 82. It is then moved toward 15 the left, feeding the work into the position shown in Fig. 2, the punch 42 being at the same time moved into position for the next perforating operation. Meanwhile the plunger 14 has begun its upward movement and 20 the spindle 18 has taken an eyelet from the raceway 70. The upward movement of the plunger 14 continues with the spindle 18 held in its uppermost position by the spring 30 until the end of the expandible upsetting 25 die is encountered by the tapered end of the spindle. The movement of the spindle is then retarded and the spring 30 yields until the upper end of the tubular holder 28 30 counters the underside of the angle piece 24. The further upward movement of the plunger 14 then subjects the spindle 18 to the pressure of the stiffer spring 32 and under 35 its actuation the portion 20 of the spindle is forced into the upsetting die expanding its sections as shown in Fig. 3. In this movement the angle piece 24 encounters the stop 36 which positively arrests further upward 40 movement of the spindle, holding the shoulder of the spindle a slight distance below the ends of the die sections. The continued upward movement of the plunger 14 with 45 the inserting die 16 slides the eyelet upwardly along the spindle 18 until the end of its barrel is forced against the upsetting surface whereupon the eyelet is clenched upon the lining portion 82 of the work as 50 shown in Fig. 3. During this setting operation it will be understood that the upsetting die is maintained in stationary position and expanded condition.

After the clenching operation the plunger 14 is immediately lowered and the end of the spindle 18 withdrawn from the upsetting die which immediately resumes its contracted condition in which it may be withdrawn through the lacing passage without obstruction. The lever 48 is finally elevated and the parts of the machine resume 60 their initial positions in readiness for a new cycle of operations.

The operation of the machine has been described in connection with the insertion of invisible eyelets but it will be apparent that

blind eyelets or other fasteners may be 65 readily inserted by presenting the work with the lining portion uppermost.

Having thus described my invention, I claim as new and desire to secure by Letters Patent of the United States:

1. An upsetting tool having a shoulder and a concave upsetting surface on the side of the shoulder toward the end of the tool; said shoulder and upsetting surface being formed in a plurality of integrally connected 75 and expandible sections.

2. An upsetting tool having a shoulder with one of its lateral surfaces forming an upsetting surface at one side of the shoulder and with its other lateral surface merging in a contracted portion at the other side, 80 said shoulder and upsetting surface being formed in a plurality of expandible but normally contracted sections.

3. An upsetting tool having an expandible 85 end portion comprising a plurality of sections having a shouldered upsetting surface formed therein, and sharp ribs each disposed midway between the edges of a section.

4. In an eyeletting machine an expandible 90 upsetting die, and a tool for expanding the upsetting die and guiding an eyelet to it.

5. In an eyeletting machine an expandible upsetting die, a raceway, and a tool for taking an eyelet from the raceway and guiding 95 it to the upsetting die when the upsetting die is in expanded condition.

6. In an eyeletting machine an expandible upsetting die, a raceway for eyelets, and a tool for taking eyelets from the raceway, expanding 100 said die, and guiding the eyelets to the upsetting die.

7. In an eyeletting machine an expandible upsetting die having a bore in its end, and a die-expanding tool having a reduced end 105 portion constructed and arranged to enter the die for a substantial distance in expanding the die and a main portion having a shoulder arranged to be disposed opposite to and adjacent to the end of the expanded 110 die.

8. In an eyeletting machine an expandible upsetting die having a central bore and resilient die sections, means for presenting 115 and upsetting an eyelet against said die, and a die-expanding tool having a tapered point and a cylindrical portion shaped to enter and fill the bore of the expanded die for a distance substantially within the end of the die to support the same during the 120 presentation and upsetting of an eyelet.

9. In an eyeletting machine an expandible upsetting die having resilient die sections, and a die-expanding tool having a portion of substantially the same diameter as 125 the diameter of the die when expanded and being disposed adjacent to the ends of the expanded sections.

10. In an eyeleting machine an expansible upsetting die, means for moving it first to enter the work and then laterally to feed the work, and an eyelet inserting tool for presenting an eyelet to the upsetting die at the conclusion of its feeding movement.
11. In an eyeleting machine a movable carrier, an expansible upsetting tool rigidly mounted thereon and a combined die-expanding and eyelet presenting tool.
12. In an eyeleting machine a movable carrier, a tubular holder adjustably mounted thereon, an adjustable abutment in one end of the holder, and an upsetting die frictionally maintained within the holder and positioned by the abutment.
13. In an eyeleting machine an expansible upsetting die, a die-expanding tool movable into engagement with the die under light spring pressure, means for arresting the movement of the tool when the die is expanded, and means for increasing the spring pressure on the die while it is so held.
14. In an eyeleting machine, an expansible upsetting die, a plunger movable toward and from the die, a tubular holder carried by the plunger and supported by a relatively heavy spring, a relatively light spring with in the tubular holder, a die-expanding tool supported by the light spring, and a stop for arresting the movement of the tool before the heavy spring is compressed.
15. In an eyeleting machine, an expansible upsetting die having a shouldered upsetting surface shaped to be passed through a hole in one of two superposed layers of sheet material and a recess above the shoulder whereby the die may be expanded without stretching the hole through which it has passed, means for presenting and setting an eyelet against said shouldered upsetting surface, and means for expanding the die prior to the setting operation.
16. An upsetting tool comprising a tubu-
- lar body portion having longitudinal slits extending from one of its ends forming expansible sections, there being formed in the sections collectively a shoulder and an upsetting surface on the side of the shoulder 50 toward the end of the tool.
17. In an eyeleting machine an expansible upsetting die, a die-expanding member, and springs of different stiffness arranged to act successively upon said member.
18. An eyelet upsetting tool having a shoulder which is formed to provide an upsetting surface on the side of the shoulder nearer the end of the tool, said shoulder and upsetting surface being formed in a plurality of expansible sections, said tool being constructed and arranged for interposition between the layers of a piece of work and for expansion when so positioned in order to provide an upsetting surface which 65 may be larger than the hole through which the tool is inserted and which is adapted to upset an eyelet forcibly presented thereagainst.
19. In an eyeleting machine, an expansible upsetting die constructed and arranged to be presented to the work from one side thereof, and means constructed and arranged to be presented to the work from the other side thereof for expanding said die 75 and presenting an eyelet against the upsetting surface thereof.
20. In an eyeleting machine, an expansible upsetting die which is normally contracted so as to be introduced through a hole in one of the layers of the work and then expanded to provide an enlarged upsetting surface, and means for inserting an eyelet through another layer of work and presenting the same against the upsetting 85 surface of said interposed die to upset the eyelet over a part of the layers of the work.
- In testimony whereof I have signed my name to this specification.

THOMAS J. HALLAM.
